UNITED STATES PATENT OFFICE

141,771

DESIGN FOR AN ANIMAL FIGURE TOY

William Smith, Detroit, Mich.

Application March 8, 1945, Serial No. 118,349

Term of patent 7 years

(Cl. D34—15)

To all whom it may concern:

Be it known that I, William Smith, a citizen of the United States, residing at Detroit, in the county of Wayne and State of Michigan, have invented a new, original, and ornamental Design for Animal Figure Toy, of which the following is a specification, reference being had to the accompanying drawing, forming part thereof, wherein:

Fig. 1 is a top plan view of an animal figure toy;

Fig. 2 is a front elevational view; and,

Fig. 3 is a side elevational view thereof, showing my new design.

I claim:

The ornamental design for an animal figure toy, as shown.

WILLIAM SMITH.
